ATTORNEY.

UNITED STATES PATENT OFFICE.

DAVID BARKER, OF CANTON, OHIO, ASSIGNOR TO THE CANTON GLASS COMPANY, OF SAME PLACE.

MOLD FOR VAULT-LIGHTS.

SPECIFICATION forming part of Letters Patent No. 404,765, dated June 4, 1889.

Application filed June 8, 1888. Serial No. 276,487. (No model.)

To all whom it may concern:

Be it known that I, DAVID BARKER, a citizen of the United States, and a resident of Canton, county of Stark, State of Ohio, have 5 invented a new and useful Improvement in Molds for Vault-Lights, of which the following is a full, clear, and exact description, reference being had to the accompanying drawings, making part of this specification.

10 My invention relates to improvements in molds for making vault-lights; and it consists of the hereinafter-described mold and of the detail and combination of parts, as set forth in the claims, the object of which is to facilitate the molding of vault-lights and to greatly reduce the cost.

Figure 1 is a side elevation of the mold, showing the parts in normal position; Fig. 2, an elevation of plunger and a sectional view 20 of fountain and upper portion of mold. Fig. 3 is a plan view of the body of the same. Fig. 4 is a sectional view of the bottom portion of the mold; Fig. 5, a plan view of same; Fig. 6, same view of mold-clamp; Fig. 7, a 25 view of an eccentric locking-pin and a portion of the handle; and Fig. 8 is a view in perspective of the light.

Similar letters of reference indicate corresponding parts in all of the figures in the 30 drawings.

A represents the bottom of the mold, in which is provided a series of circular apertures B, having a countersink about the upper portion to form the under side b of the projected head portion a of the light L, and about the upper portion of said part is provided an annular rib D, flat or plain on the top, as shown at d, and beveled on its lower side, as shown at f. In the face of said portion A is provided a recess E, to receive a downwardly-projected portion F of the upper portion G of the mold, and in the bottom of said portion A is provided a recess H, in which is fitted a circular plate I, to which is secured a series of plungers J, adapted to the apertures B. The upper portion of said plungers being cut away to a line of about forty-five degrees, as shown at M, Fig. 4, to form the reflecting-face N of the light L, the 45 said recess H should be at least one-half inch

deeper than the thickness of the plate I, and the parts assembled about as shown in Fig. 4.

The upper portion G of the mold, having its lower face adapted to the recess E in the bottom portion A of the mold, as hereinbefore stated, is also provided with a series of depressions, as K, corresponding with the apertures in the bottom portion A to form the top or head portion a of the light L, as shown in Fig. 8, and also with a centrally-located 55 aperture O as a fountain, with which the depressions K are connected by a communicating sprue P, through which the fused glass is forced by the descent of the plunger J into the mold formed by the depression K in the top portion and the aperture B in the bottom portion. About the top portion G there is also provided an annular rib Q, similar in form to rib D about the bottom portion A.

A clamp R is formed substantially as shown 70 in Figs. 1 and 6, consisting of two semicircular portions S and S', pivotally secured together, as shown at T, part S having at its free end two ears g and g', and portion S' a single ear h. Each of said ears is centrally 75 perforated, as k k'. The perforation k' in the ear g' is smaller than perforation k in ear g, and is adapted to the smaller portion l of the eccentric locking-pin U, the eccentric portions m being adapted to the perforation k. 80

On the inner face of the clamp so formed there is provided a V-shaped groove, as indicated by the dotted lines W, adapted to embrace the ribs D and Q, resting on the beveled faces f and n. To secure the parts, the 85 locking-pin U is placed in the perforations in the ears referred to, and is rotated by the handle X into a locked position, the parts being held in registered relation by the dowel-pin y in perforation y', and together by the 90 pressure of the clamps on the beveled face of the ribs D Q.

The operation is as follows: The mold is clamped together, as shown in Fig. 1, the plunger Z removed, a desired amount of fused 95 glass is dropped into the fount O, the plunger returned, and the mold placed under a press adapted for such purpose, the plunger forced down, and the fused glass driven through the sprues P into the mold formed by the aper- 100

ture B and the recess W, forming a vault-light, as L, shown in Fig. 8 having a head, as a, and an angular reflecting-face, as a'. To remove the light from the mold, the clamp 5 R is removed, the top portion of the mold lifted off, the lower portion turned on its side, and the bottom plate I pressed in, by which the plungers J will be carried into mold-aperture to force the light out.

10 Having thus fully described the nature and object of my invention, what I claim, and desire to secure by Letters Patent, is—

15 1. In a vault-light mold, the combination of the bottom part A, having a series of perforations B, an annular peripheral rib D, recess H, and a bottom plate I, having a series of plungers J secured thereto and adapted to enter the perforations B, said plungers cut away at the upper portion to a line of angularity of about forty-five degrees from a line 20 drawn vertically through the center of the

plungers, substantially as described, and for the purpose set forth.

2. In a vault-light mold, a top portion G, having a series of depressions K, a central 25 fount, as O, and communicating sprues P, and an annular rib Q, substantially as described, and for the purpose set forth.

3. The combination of the bottom portion A, having a series of perforations B, recess H, 30 plate I, plungers J, annular ring D, a top portion G, having depressions K, sprues P, fount O, annular peripheral rib Q, plungers Z, and locking-clasp R, substantially as described, and for the purpose set forth.

In testimony whereof I have hereunto set my hand this 1st day of June, A. D. 1888.

DAVID BARKER.
